UNITED STATES PATENT OFFICE.

BERT COLEMAN, OF PLATTSMOUTH, NEBRASKA.

DISPLAY RACK.

Application filed March 3, 1928. Serial No 258,801.

This invention relates to certain new and useful improvements in racks for use in displaying articles in stores, and has more particular reference to an improved rack of this kind wherein provision is made by which the articles may be readily placed in position and any one article removed when desired without disturbing the others.

A more specific object is to provide an improved display rack for garment-supporting belts and like articles, wherein holders are provided which embody spring-pressed followers or presser members so arranged that, as soon as one or a number of articles are withdrawn from the holders, the presser members will serve to effectively hold the articles remaining.

Another object is to provide holders which are readily adjustable to properly accommodate articles of different widths.

Still another object is to provide a display rack of the above kind, which is simple and durable in construction, efficient in operation, adapted to be conveniently placed into practical use, and economical to manufacture.

Other objects will become apparent as the nature of the invention is better understood, and the same consists in the novel form, combination and arrangement of parts herein-after more fully described, shown in the accompanying drawings and claimed.

In the drawings:

Figure 1 is a side elevation of a display rack embodying the present invention.

Figure 2 is an enlarged top plan view thereof, partly broken away and in section.

Figure 3 is an enlarged fragmentary elevation, showing one of the gates, for closing the fronts of the holder compartments, in open position.

Figure 4 is an enlarged fragmentary section on line 4—4 of Figure 2.

Figure 5 is an enlarged perspective view of one of the presser members and its guide pin; and

Figure 6 is an enlarged perspective view of one of the slides for adjusting the effective width of the holder compartments.

Referring more in detail to the drawings, the form of holder shown embodies a stand A, a frame B having a number of open-bottomed compartments, and presser members C slidably fitted in the compartments of said frame and each spring-pressed toward the front wall of the associated compartment to hold a number of belts or other articles and

permit the latter to be suspended below the compartments.

The stand A consists of a base 5 and a vertical post 6 of sufficient strength and length to carry at or near its upper end the frame B with the articles suspended from said frame in the desired position for exhibition and easy access.

The frame B has a number of compartments 7 formed by vertical walls, and each compartment is open at the top and bottom and has its opposite side walls formed with horizontal guide grooves 8. At the center the frame is formed or provided with a bearing 9 fitted to turn upon the upper end portion of the part 6. The shape and size of the frame and the number, size and arrangement of the compartments therein may be varied according to the nature and quantity of the articles to be displayed and other conditions. In a like manner, the frame may be supported in other ways than by a stand.

The presser members C are slidably fitted in the several compartments of the frame B, one to each compartment, and having reduced ends 10 slidably engaged in the guide grooves 8. Each presser member consists of a bar or plate having a central rigid guide pin 11 projecting rearwardly therefrom and slidably projecting into a bore 12 provided in the frame at the rear of the associated compartment, a helical compression spring 13 being interposed between the pin and the frame, within the bore 12 and a bore in the rear end 90 of the pin, to force the presser member toward the outer or front wall of the associated compartment. The presser members may thus be forced rearwardly or inwardly to permit the desired number of articles to be placed in the compartments outwardly thereof, whereby, when the presser members are subsequently released, the articles will be firmly gripped between the presser members and the outer walls of the compartments so that the articles are held in suspension to hang below the compartments. As the springs 13 are not of great strength or tension, the articles will be held lightly enough to permit one or more of the articles to be withdrawn upwardly from any desired compartment without disturbing the remaining articles in such compartment.

As shown, the frame B may be formed of a series of substantially sector-shaped plate-like sections 14 rigidly connected with adjacent side edges thereof contiguous, each sec-

- tion constituting a holder and having a single compartment 7 formed in its outer end. The outer end of each compartment is preferably closed by a gate 15 adapted to be opened to facilitate placing of the articles in the compartment, means, such as a hasp fastener 16, being provided to releasably hold the gate closed where it forms the outer wall of the compartment against which the articles are pressed.
- 10 The compartment of each frame section is shown as formed by bifurcating or notching the outer end of the frame section, the gate 15 being preferably hinged at one end to the frame section, as at 17. Stop pins 18 are provided in the outer end portions of the grooves 8 in the path of the ends of the presser members to limit outward movement of the latter and prevent their displacement from operative position when the gates are opened.
- 15 20 It very often happens that the articles to be displayed, such as trouser-supporting belts are of different widths. Obviously, in order to properly hold articles of different widths in an orderly and efficient manner within any 25 desired ones of the several compartments, the latter must be adjustable as to effective width. For this purpose, slides 19 are provided at opposite sides of each compartment, the slides being laterally adjustable toward each other 30 inwardly of the side walls of the compartment proper for adjustably narrowing the normal effective width of the latter, when desired. These slides preferably consist of metal plates disposed on top of the frame and having transversely elongated slots 20 through which clamping bolts 21 extend, the bolts 21 passing through the frame and having nuts 22 applied thereto for being tightened to secure the slides in any desired position of adjustment.
- 35 40 The slides have straight depending flanges 23 on their inner edges for flat engagement with the opposite edges of the articles as shown in Figures 2 and 4, the flanges terminating above the presser members to permit unhindered movement of the latter.

In use, each gate 15 is opened and the associated presser member is forced rearwardly,

whereupon the articles are introduced through the gateway into the compartment. The gate is then closed and latched in closed 50 position, the presser member being released to clamp the articles against the closed gate. The slides 19 are then adjusted against the side edges of the articles, if necessary, whereupon the device is ready for displaying the 55 suspended articles. Any desired ones of the articles may then be readily selected and withdrawn upwardly from the rack as occasion may demand, without disturbing the remaining articles.

Various changes in minor details of construction and arrangement of parts may be made within the spirit and scope of the invention as claimed.

What I claim as new is:

1. In a display rack, a frame member having an open-bottomed compartment, a presser member carried by the frame member and slidably mounted in said compartment for cooperation with the front wall of the latter 70 to hold articles in suspension, spring means acting against said presser member for urging it toward said front wall of the compartment, means to adjust the effective width of said compartment embodying laterally adjustable 75 slides mounted on the frame member at opposite sides of said compartment.

2. In a display rack, a frame member having an open-bottomed compartment, a presser member carried by the frame member and slidably mounted in said compartment for cooperation with the front wall of the latter 80 to hold articles in suspension, spring means acting against said presser member for urging it toward said front wall of the compartment and a gate member forming the front wall of said compartment and adapted to be opened to facilitate insertion of the articles into the compartment, said gate being hinged at one end to the frame member, and means 85 to latch said gate in closed position.

In testimony whereof I affix my signature.

BERT COLEMAN.
